UNITED STATES PATENT OFFICE

157,943

TIRE GAUGE TESTER OR SIMILAR ARTICLE

Harold G. Cooper, Los Angeles, Calif., assignor to
Union Oil Company of California, Los Angeles,
Calif., a corporation of California

Application April 12, 1948, Serial No. 145,658

Term of patent 7 years

(Cl. D52—1)

To all whom it may concern:

Be it known that I, Harold G. Cooper, citizen of the United States and residing at Los Angeles, Los Angeles County, California, have invented a new, original, and ornamental Design for a Tire Gauge Tester or Similar Article, of which the following is a specification, reference being had to the drawing, forming part thereof.

The figure is a perspective view of a tire gauge tester, showing my new design.

I claim:

The ornamental design for a tire gauge tester or similar article, substantially as shown.

HAROLD G. COOPER.
